PANEL FASTENER

Emil C. Loetscher, Dubuque, Iowa

Application December 27, 1935, Serial No. 56,390

5 Claims. (Cl. 292—202)

The object of this invention is to improve the construction of fasteners for removably securing screen or glazed panels in door or other openings in a manner to prevent dislodgment of the 5 fasteners due from various causes such as severe slamming of the door when blown by the wind.

A further object of the invention is to improve the construction of the fastener, to reduce its cost and to facilitate assembly thereof in the 10 frame of the opening.

With these and other objects in view, as will be pointed out as the description progresses, reference will be had to the accompanying drawing, wherein:

15 Fig. 1 is a view in front elevation with parts broken away and shown in section to illustrate underlying parts.

Fig. 2 is a view in front elevation.

Fig. 3 is a transverse sectional view taken on 20 the line 3—3 of Fig. 2, and

Fig. 4 is a view in side elevation of the fastener with non-contracted ferrule projected in dotted lines.

25 In the drawing, reference numeral 2 designates a door or other stile and 3 the stile of the removable panel, which latter may carry a window pane 4 or in lieu thereof, an insect screen. The stiles 2 and 3 are conventionally rabbeted to provide overlapping flanges 5 and 6 respectively and shoulders 7 and 8 respectively. Well in the plane 30 of the flange 6, the stile 2 is provided with an arcuate saw kerf or slot 9 and coinciding therewith is an arcuate cut 10 formed in the stile 3. The kerf or slot in the stile 2 is in a plane parallel 35 with the plane of said stile, while the slot in the stile 3 may be in the same plane or one slightly inclined with respect thereto to effect a camming action to draw the flanges 5 and 6 tightly together by the action of the turn-button plate 12 working in said kerfs or slots.

40 A distance back from the shoulder 7 of the stile 3 is bored a countersink 14 leading to a bored hole 15 that terminates in a shoulder 16. A smaller hole 17, of a diameter to accommodate the stem 45 of the fastener to be described, is then provided in the bottom of the hole 15, thereby providing the aforesaid shoulder 16. The hole 17 does not penetrate through the stile 2.

50 The stem of the fastener comprises a cylindrical bottom end 20, below a square shank portion 21, above which is the circular head flange 22 and head 24, the latter being provided with a slot 25 to receive a screw-driver or other rotating implement. The stem is formed in a swaging or forg-

ing machine from stock of the diameter of the cylindrical end 20.

The turn-button plate 12 is elongated and has rounded ends 26 and a central square opening 27 loosely receiving the square shank 21 of the stem 5 so that the plate 12 may cant and work in a slot in the panel style that is either parallel or inclined with respect to the plane of the panel stile 3.

10 The device is assembled by inserting the stem into the prepared holes with the cylindrical end 20 and square shank 21 within the bore 17, but out of contact with its walls. The head flange 22 rests and turns upon the shoulder 16 and the entire stem is confined in position by a split spring 15 ferrule 28 normally of greater internal diameter than the external diameter of the head 24. This ferrule is placed upon the counterbore 14 and driven down thereon, whereupon the inclination of the counterbore will cause the ferrule to contract until it enters the smaller bore 15 and conforms to the size thereof. It is then driven straight down, and since it normally tends to expand, the wood of the stile in which it is embedded tends to enter the indentations 29 and to thereby 20 prevent its displacement. Obviously, small burrs which would dig into the wood could be substituted for the indentations, and in fact the operation of indenting naturally throws up small 25 projections at the margins of the indentations. Thus, the roughened expanding ferrule 28 acts to retain itself as well as the turn-button operating stem in place against being thrown out under heavy shocks such as are occasioned by 30 severe slamming of the door when blown shut by 35 winds.

What is claimed:

1. A fastening device for locking two slotted members together; one member being provided with a large and a small bore providing a shoulder between them; a turn-button plate rotatably arranged within the member having the bores to engage the other said member; a stem within the smaller bore associated with the turn-button 40 plate to operate the same; an enlarged operating head upon said stem rotatably seated upon said shoulder and within the larger bore; and a contracted spring ring within the large bore and expanding to grip the walls thereof and being engaged with the said head to confine the same upon the shoulder and the stem against displacement. 45

2. A fastening device for locking two slotted-members together; one member being provided with a large and a small bore providing a 50

- shoulder between them; a turn-button plate rotatably arranged within the member having the bores to engage the other said member; a stem within the smaller bore associated with the turn-button plate to operate the same; an enlarged operating head upon said stem rotatably seated upon said shoulder and having a reduced peripheral portion; and a spring ring within the large bore and reduced peripheral portion of the head and expanding to grip the walls of the bore to confine the head upon the shoulder and the stem against displacement.
3. A fastening device for locking two slotted members together; one member being provided with a large and a small bore providing a shoulder between them; a turn-button plate rotatably arranged within the member having the bores to engage the other said member; a stem within the smaller bore associated with the turn-button plate to operate the same; an enlarged operating head upon said stem rotatably seated upon said shoulder and having a reduced peripheral portion; and a spring ring within the large bore and reduced peripheral portion of the head and expanding to grip the walls of the bore to confine the head upon the shoulder and stem against displacement; said ring serving to center said head within the large bore and to form a bearing therefor.
4. A fastening device for locking two members together; one member being provided with a large and a small bore and a countersink for the large bore; a shoulder between the two bores; a circular operating head rotatably seated upon said shoulder and provided with a projecting peripheral flange adjacent said shoulder; a spring ring of less diameter than the largest part of the
- countersink and of greater normal diameter than that of the large bore; said ring being contracted within the large bore and expanding against the walls thereof and bearing against said flange to confine the head upon said shoulder, said ring further serving to center said head within the large bore and to form a bearing therefor; a turn-button plate within the member having the bore for engaging the other member, and means non-rotatably connecting said head and turn-button plate.
5. A fastening device for locking two slotted members together; one member being provided with a large and a small bore and a countersink for the large bore; a shoulder between the bores; a circular operating head rotatably seated upon said shoulder and provided with a projecting peripheral flange adjacent said shoulder; a split externally roughened ring of less diameter than the largest part of the countersink and of greater normal diameter than that of the bore; said ring being contracted within the large bore and expanding against the walls thereof and bearing against said flange to confine the head upon said shoulder, said ring when within the large bore having an internal diameter of a dimension to permit the ring to form a bearing for the head and to center the same within the bore; a stem concentric with the head and arranged within the small bore and being non-circular in cross-section; and a plate rotatably arranged within the member having the bores and adapted to lock the members together; said plate having a non-circular opening for non-rotatably receiving the said non-circular stem.
